UNITED STATES PATENT OFFICE

WILLIAM C. DEVEREAUX, OF DETROIT, MICHIGAN

DOORLATCH MECHANISM

Application filed October 10, 1932. Serial No. 637,175.

This invention relates generally to door latch constructions and refers more particularly to the outside handle hub or rollback structure thereof.

5 One of the essential objects of the invention is to provide a one piece rollback with means for taking up play between the rollback and handle stem and for normally holding the stem and handle in a predetermined position when the parts are installed in a vehicle door.

10 Another object is to provide a structure which comprises fewer parts and can be more economically manufactured than sectional rollback assemblies.

15 Other objects, advantages and novel details of construction will be made more apparent as this description proceeds, especially when considered in connection with the accompanying drawing, wherein:

20 Figure 1 is a fragmentary elevation of a vehicle door with latch mechanism embodying my invention applied thereto;

25 Figure 2 is a sectional view taken on the line 2—2 of Figure 1;

Figure 3 is an enlarged detail view of the rollback;

30 Figure 4 is an edge elevation of the rollback illustrated in Figure 3;

Figure 5 is a detail view of the tension spring;

35 Figure 6 is an edge elevation of the spring illustrated in Figure 5.

Referring now to the drawing, 1 is a vehicle door; 2 is a latch case plate secured to the inner side of the door and having a lateral flange 3 at its forward edge secured to the free edge of the door; 4 is a latch bolt extending through an opening in the flange 3 for engagement with a suitable keeper (not shown) and having a shank 5 slidably mounted on the case plate 2, and 6 is a spring anchored on the case plate and having an arm 7 engaging the shoulder 8 of the shank and normally holding the bolt 4 in projected position. 9 is a cover plate arranged in spaced relation to the case plate 2 and rigidly secured thereto and to the flange 3, and 10 is a handle operable from the outer side 40 of the door and having a stem 11 of substan-

tially square cross section disposed substantially parallel to the lateral flange 3 of the case plate and extending through aligned circular openings 12 and 13 respectively in the case plate 2 and cover plate 9. 55

In the present instance I have mounted a one piece rollback 14 of special design upon the handle stem 11 for effecting a retraction of the bolt 4 from the outer side of the door and have provided a tension spring 15 for taking up play between the rollback 14 and stem 11 so that the latter will be prevented from rattling and the handle 10 will be held in the proper horizontal position upon the outer side of the door. 60

As shown, the rollback 14 comprises a relatively thick plate having arm portions 16 and 17 and a laterally projecting circular hub portion 18. Preferably the rollback is located between the case plate 2 and cover plate 9 with the hub portion 18 in the circular opening 12 in the case plate and the arm portion 16 between the lateral flange 3 and a shoulder 19 of the bolt shank 5. The other arm portion 17 extends rearwardly below the shoulder 19 and is adapted to be engaged in the usual way by a suitable dogging member (not shown) when it is desired to render the outside handle 10 inoperative from the inside of the door. 65

Figure 1 is a fragmentary elevation of a vehicle door with latch mechanism embodying my invention applied thereto;

Figure 2 is a sectional view taken on the line 2—2 of Figure 1;

Figure 3 is an enlarged detail view of the rollback;

Figure 4 is an edge elevation of the rollback illustrated in Figure 3;

Figure 5 is a detail view of the tension spring;

Figure 6 is an edge elevation of the spring illustrated in Figure 5.

Referring now to the drawing, 1 is a vehicle door; 2 is a latch case plate secured to the inner side of the door and having a lateral flange 3 at its forward edge secured to the free edge of the door; 4 is a latch bolt extending through an opening in the flange 3 for engagement with a suitable keeper (not shown) and having a shank 5 slidably mounted on the case plate 2, and 6 is a spring anchored on the case plate and having an arm 7 engaging the shoulder 8 of the shank and normally holding the bolt 4 in projected position. 9 is a cover plate arranged in spaced relation to the case plate 2 and rigidly secured thereto and to the flange 3, and 10 is a handle operable from the outer side 40 of the door and having a stem 11 of substan-

able slots 27 and 28 respectively in the rollback 14 so that a separable but firm driving connection is provided between the spring 15 and the rollback 14.

5. Thus when the parts are assembled the spring 15 will move with the rollback 14 and in doing so will take up any play between the rollback and stem 11. Moreover the construction is such that when the rollback arm 10 is held against the case plate flange 3 by the spring pressed shoulder 19 the stem 11 will be prevented from rattling and the handle 10 will be yieldingly held in proper horizontal position upon the outer side of the 15 door.

What I claim as my invention is:

1. In a door latch, a handle stem, a one piece rollback on the stem, and means for taking up play between the rollback and stem 20 including means rotatable in a cover plate for the rollback and having oppositely extending portions, one of said portions having an opening receiving the stem and lugs in the edges of the opening under tension and 25 pressing against the stem, and the other of said portions engaging the rollback and having lugs interlocked therewith.
2. In a door latch, a handle stem, a one piece rollback on the stem, and means for 30 taking up play between the rollback and stem including a member of yieldable material rotatable in a cover plate for the rollback and having a web and a peripheral flange, the web having an opening receiving the stem 35 and lugs under tension engaging the stem, and the flange bearing against one side of the rollback and having laterally projecting lugs interlocked therewith.
3. In a door latch, a pair of substantially 40 parallel plates, a rollback between said plates in spaced relation to one of them and having a laterally projecting hub mounted to turn in the other, a handle stem extending through the hub, and means for taking up play between the rollback and stem including a member of yieldable material mounted to turn 45 in the other of said plates, having portions pressing against said stem and having other portions connected to the rollback.
50. 4. In a door latch, a case plate, a cover plate substantially parallel to the case plate, a rollback between said plates and having a hub rotatably mounted in one of them, a handle stem extending through said hub, and 55 means for taking up play between the rollback and stem, including a member of yieldable material rotatably mounted in the other of said plates, having portions pressing against said stem and having other portions connected to the rollback.
60. 5. In a door latch, a case plate, a cover plate substantially parallel to the case plate, a rollback between said plates and having a hub rotatably mounted in one of them, a handle 65 stem extending through said hub, and means

for taking up play between the rollback and stem, including a member of yieldable material rotatably mounted in the other of said plates and having oppositely extending portions, one of said portions having an opening 70 receiving the stem and parts under tension pressing against the stem, and the other of said portions being disposed at one side of the rollback and having parts interlocked therewith.

6. In a door latch, a pair of substantially parallel plates having aligned openings therein, a handle stem of substantially square cross section extending through said aligned openings, and a rotary support for said stem in said openings including two interlocked members movable between said plates and having laterally projecting portions journaled in said aligned openings, one of said members being a rollback and having an arm for engagement with the shank of a latch bolt, and the other of said members terminating short of the arm and having yieldable means pressing against said stem and taking up play between the rollback and stem. 90

7. In a door latch, a pair of substantially parallel plates having aligned openings therein, a handle stem of substantially square cross section extending through said aligned openings, and a rotary support for said stem in said openings including two members movable between said plates and having complementary portions journaled in said aligned openings, one of said members being a one piece rollback and having an arm for engagement with a shank of a latch bolt, and the other of said members being non-rotatively connected to the rollback and having lugs of spring metal pressing against opposite sides of the stem whereby play is taken up between the stem and rollback. 100

8. In a door latch, a pair of substantially parallel plates having aligned openings therein, a handle stem extending through said aligned openings, and a rotary support for said stem in said openings including two members movable between said plates and having complementary portions journaled in said aligned openings, one of said members being a rollback and being more than twice as thick as the other, and the other of said members being formed from spring metal and having an area less than that of the rollback, said other member being non-rotatively connected to the rollback and having lugs pressing against the stem whereby play is taken up between the stem and rollback. 110

9. In a door latch, a pair of substantially parallel plates having aligned openings therein, a handle stem extending through said aligned openings, and a rotary support for said stem in said openings, including two members movable between said plates and having complementary portions journaled in said aligned openings, one of said members

being a rollback and having notches therein at substantially diametrically opposite points thereof, and the other of said members having laterally projecting lugs engaging said notches and having lugs of yieldable material pressing against said stem whereby play is taken up between the stem and rollback.

10. In a door latch, a pair of substantially parallel plates having aligned openings therein, a handle stem of substantially square cross section extending through said aligned openings, and a rotary support for said stem in said openings including two members having complementary portions journaled in said aligned openings, one of said members being a rollback and having an arm movable between said plates for engagement with a shank of a latch bolt, and the other of said members being non-rotatively connected to the rollback and having yieldable means pressing against opposite sides of the stem whereby play is taken up between the stem and rollback.

11. In a door latch, a pair of substantially parallel plates having aligned openings therein, a handle stem extending through said aligned openings, and a rotary support for said stem in said openings including two members having complementary portions journaled in said aligned openings, one of said members being more than twice as thick

as the other and having an arm movable between said plates for engagement with a shank of a latch bolt, and the other of said members being formed from light gauge spring metal and having an area less than that of the first mentioned member, said other member being non-rotatively connected to the first mentioned member and having yieldable means pressing against the stem whereby play is taken up between the stem and first mentioned member.

12. In a door latch, a pair of substantially parallel plates having aligned openings therein, a handle stem extending through said aligned openings, and a rotary support for said stem in said openings, including two members having complementary portions journaled in said aligned openings, one of said members having notches therein at substantially diametrically opposite points thereof and having an arm movable between said plates for engagement with a shank of a latch bolt, and the other of said members having laterally projecting lugs engaging said notches and having yieldable means pressing against said stem whereby play is taken up between the stem and first mentioned member.

In testimony whereof I affix my signature.

WILLIAM C. DEVEREAUX.
